SAFETY COUPLING FOR STIRRUPS

Filed April 14, 1948

UNITED STATES PATENT OFFICE

2,537,532

SAFETY COUPLING FOR STIRRUPS

Eduard Hrabal, Washington, D. C., assignor of
thirty-five per cent to Rafael Dominguez,
Washington, D. C.

Application April 14, 1948, Serial No. 20,956

1 Claim. (Cl. 54—49)

1

This invention relates to a safety coupling for a stirrup and has for its primary object to disengage a stirrup from its suspension strap when the weight of the user is shifted as by falling.

Another object is to avoid injury to a horseman through being dragged with his foot caught in the stirrup.

The above and other objects may be attained by employing this invention which embodies among its features a pair of jaws pivoted together at one end, suspension means at the pivoted ends of the jaws, yielding means to hold the jaws closed, interdigitating pins carried by the jaws remote from the pivoted ends thereof, a stirrup, a suspension plate on said stirrup and said suspension plate having openings therein for receiving the pins and supporting the stirrup on the coupling when the jaws are closed and the pins are in interdigitating relation.

Other features include latch means carried by the stirrup positively to hold the jaws closed.

In the drawings:

Figure 1 is a perspective view of a stirrup and safety coupling therefore showing the parts assembled and ready for use;

Figure 2 is an end view in elevation of the stirrup shown in Figure 1;

Figure 3 is a view similar to Figure 2 showing the suspension means in the act of releasing the stirrup;

Figure 4 is a horizontal sectional view taken substantially along the line 4—4 of Figure 2;

Figure 5 is a vertical sectional view taken substantially along the line 5—5 of Figure 2, and

Figure 6 is a perspective view of the latch.

Referring to the drawings in detail a stirrup 10 is equipped with a conventional foot rest 12 and arch shaped yoke 14 which serves as the suspension means for the foot rest 12, as in a conventional stirrup. Projecting upwardly from the top of the arch 14 is a suspension plate 16 which as illustrated in Figure 4 is provided with a row of openings 18 for the reception of the interdigitating suspension pins to be more fully hereinafter described.

Pivottally connected together at one end as at 20 is a pair of jaws 22 forming a part of the safety coupling of the stirrup. The ends of the jaws 22 remote from the pivot 20 are cut away as at 24, and are provided with spaced transversely extending openings 26 in which interdigitating pins 28 are fixed. As shown in Figure 3 the pins extend toward one another beyond the cut away portions 24 of the jaws 22, and when the jaws are closed, these pins lie in interdigitating rela-

2

tion as illustrated in Figure 4. Extending around the pivoted ends of the jaws 22 is a U-shaped spring 30 which is adapted yieldingly to hold the jaws in closed position with the pins 28 in interdigitating relation. A suitable strap receiving eye 32 is coupled to the pivot 20 for the reception of a conventional stirrup strap by which the stirrup is suspended from a conventional saddle.

Pivottally coupled as at 34 to the arch 14 of the stirrup 10 adjacent the suspension plate 16 thereof is a latch designated generally 36 which comprises a U-shaped body 38, opposite legs 40 of which are adapted when the latch is in latched position as shown in Figures 1 and 2 to overlie the lower ends of the opposite jaws 22 in order to prevent them from moving about their pivot 20 and carrying the pins out of interdigitating relation.

In the preferred embodiment of the invention 20 the pins 28 are provided in their upper sides with notches 42 which when the pins are in interdigitating relation are adapted to align, and formed on the suspension plate 16 and extending through the openings 18 therein are lugs 44 which are 25 adapted to engage in the notches to cooperate therewith in forming surfaces about which the suspension plate 16 may rock relative to the jaws.

In use the coupling is suspended from a conventional saddle strap by passing the strap through the eye 32 and spreading the jaws 22 to insert the suspension plate 16 in place between the cut away portions 24 of the jaws. Upon releasing the force holding the jaws open, the spring 30 will cause the ends of the jaws remote from the pivoted ends to approach one another and move the pins 28 into interdigitating relation within the openings 18 of the plate 16. In this position the bottom edges of the lugs 44 will seat in the notches 42 to facilitate a slight rocking movement of the stirrup 10 relative to the suspension means. With the latch 36 thrown into the position illustrated in Figure 3, it will be obvious that the legs 40 thereof will be out of engagement with the jaws 22, thus allowing the device to function in a normal manner so that when the rider becomes overbalanced and his weight changes relative to the stirrup and coupling, the stirrup may rock as suggested in Figure 3 and force the jaws to open against the effort of the spring 30 so that the pins 28 become withdrawn from the openings 18 and the stirrup is then free to fall out of position with relation to the coupling. In this way any danger of the rider becoming dragged along the ground and possibly seriously injured may be avoided. Should

the rider so desire however it is evident that by moving the latch 36 into the position illustrated in Figures 1 and 2, the jaws will be held against opening.

While in the foregoing there has been shown and described the preferred embodiment of this invention it is to be understood that minor changes in the details of construction and arrangement of parts may be resorted to without departing from the spirit and scope of the invention as claimed. 10

Having described the invention, what is claimed as new is:

A safety stirrup comprising a pair of jaws pivoted together at their upper ends, means at the pivoted ends for suspending the jaws on a strap, yielding means to hold the jaws closed, interdigitating pins carried at the lower end of said jaws and including notches in their upper surfaces, a suspension plate on said stirrup extending between the lower end of said jaws, said plate including apertures for receiving said pins and detents in said plate extending into said apertures 15

5

adapted to engage said notches on said pins, and latch means pivoted to said stirrup selectively to hold the jaws closed.
